CLAIM

(21) Appl. No.: **29/165,762**

The ornamental design of a point discharge dissipation terminal, substantially as shown and described.

(22) Filed: **Aug. 16, 2002**

DESCRIPTION

(51) LOC (7) Cl. **10-05**

FIG. 1 is a front elevational view of a point discharge dissipation terminal in accordance with the subject invention.

(52) U.S. Cl. **D10/105**

FIG. 2 is a back elevational view of the dissipation terminal seen in FIG. 1.

(58) Field of Search ..... D10/105; 174/2, 174/3, 4 R, 4 C, 5 R, 6, 7; 361/212, 220-224

FIG. 3 is a right side elevational view of the dissipation terminal seen in FIG. 1.

(56) **References Cited**

FIG. 4 is a left elevational side view of the dissipation terminal seen in FIG. 1.

U.S. PATENT DOCUMENTS

FIG. 5 is a top elevational view of the dissipation terminal seen in FIG. 1.
